UNITED STATES PATENT OFFICE.

PERCY HECTOR PITMAN, OF LONDON, ENGLAND.

CONTROLLING DEVICE FOR JET-IMPELLED WATER TURBINES.

Application filed September 15, 1926, Serial No. 135,669, and in Great Britain April 7, 1925.

This invention relates to the controlling devices of impulse turbines of the Pelton wheel type of the kind provided with a jet deflector and has for its object improvements in the construction thereof whereby the same can be operated with a minimum of power and efficient governing can be obtained.

Controlling devices of the kind referred to, as heretofore constructed, have employed a deflector consisting of an inclined plate carried by pivoted arms connected to a governor by which the said plate was caused to enter the jet so as to divert a suitable portion of the water from the blades of the turbine while the supply was being gradually curtailed in order to maintain the desired speed under different conditions of load.

Owing to the resistance to be overcome when a deflector of the kind referred to is inserted into a high pressure jet considerable energy was required to actuate it and this necessitated in the case of large units the employment of auxiliary apparatus which delayed its controlling action and rendered the governing less sensitive and inefficient.

In order to overcome the foregoing difficulties the present invention comprises a balanced deflector that is acted upon by the jet at two points in such a way as to tend to turn it in opposite directions about its point of support. As the forces applied at these points are substantially equal they balance each other with the result that a minimum effort is required to turn the improved deflector.

In some cases the improved deflector is coupled to a needle valve that controls the diameter of the water jet. For this purpose the needle or spear is provided with means of retarding its movement in the direction to cut off the water supply (so as to avoid the dangerous pressure that would be caused by the momentum of a large body of water when its movement is suddenly arrested) and is coupled to the deflector (whose movement may be controlled by a hand wheel or a suitable governor) through an elastic connection that yields when the movement is in the direction to close the valve but immediately transmits movement in the direction to open it.

According to one mode of carrying out the present invention a tubular deflector journalled on trunnion bearings is supported

coaxially with the jet, which, when the turbine is running with a full load passes centrally through the bore of the deflector.

When the deflector is turned in its bearings one side of its outer surface at the end nearest the nozzle and the other side of its inner surface at its opposite end are brought into contact with the jet so as to deflect more or less of the water away from the buckets of the turbine according to the angle through which the deflector is turned. The contour of the inner and outer surfaces of the deflectors are of such configuration that the tendency of the jet to turn the deflector in one direction by reason of its impinging against one end is counteracted by the tendency to turn it in the opposite direction by reason of the impingement of the said jet against the opposite end of the deflector.

The deflector may be operated by a hand lever mounted on or connected to one of its trunnions by suitable linkage or it may be operated by a hand wheel or a governor suitably connected to an arm secured to the deflector. This linkage may also impart longitudinal movement to the spear of a jet-controlling valve through a spring.

In order to prevent the too-rapid closing of the valve the spear is provided with a dash-pot or oil cylinder and has two shoulders between which is situated a sleeve connected to a lever, hand wheel or governor through the aforesaid linkage. A spring is situated between the forward end of the sleeve and the shoulder on that side so that when the linkage is operated in the direction to close the valve the spring will be compressed and will slowly urge the spear forward at a speed controlled by the dash-pot.

When the movement is in the opposite direction the sleeve will directly engage the rear shoulder and immediately withdraw the spear to the extent determined by its operating means.

I will now describe my invention more particularly with the aid of the accompanying diagrammatic drawings in which—

Fig. 1 shows in vertical section one embodiment of the improved deflector and controlling gear in the full load position, as applied to a Pelton wheel.

Fig. 2 is a similar view showing the parts in their respective positions after the load has been removed.

Fig. 3 is a detail showing a similar view

of the deflector in the position it takes up after the jet has been reduced by the controlling valve to suit the reduced load,

Fig. 4 is a plan view of the deflector and jet nozzle and

Fig. 5 is a front view of the deflector when in the full load position.

According to the construction shown in the drawings *a* represents the buckets of a 10 Pelton wheel and *c* the nozzle by which a jet *d* of high pressure water is directed on to the said buckets so as to rotate the wheel and drive the turbine.

When the load is reduced the speed of the 15 motor will increase unless the rod *e* be moved in the direction of the arrow in Fig. 1 so as to move the parts towards the position shown in Fig. 2.

The rod *e* may be operated by a lever, 20 hand wheel or any suitable governor through suitable linkage as hereinbefore stated.

The deflector *f* is of tubular form and is provided with trunnions *g* journalled in bearings *h* (Fig. 4) formed integrally with 25 or bolted to the nozzle *c*. When the said deflector is turned on its trunnions in the direction indicated in Fig. 1 its inner surface *i* at its forward end will deflect the jet *d* in a downward direction away from the buckets 30 *a*, and the rear edge *j* of the deflector will cut into the said jet and so divide it into two parts *d* and *d*¹.

During this process the pressure of the 35 jet *d* on the surface *i* will tend to turn the deflector in a counterclockwise direction and the pressure of the jet *d*¹ on the under surface *k* of the said deflector which will tend to turn it in a clockwise direction with an equal force that will counteract the effect 40 of the jet *d* on the surface *i* thus enabling the deflector to be actuated with a minimum amount of energy.

In order to obtain a steady action of the 45 deflector the end of the surface *i* and the edge *j* should not be too far from the point about which the deflector turns and so as to produce the necessary compensating lift at *j* the surface *k* is so formed as to enable the jet *d*¹ to apply a force to the deflector that 50 will tend to turn it in the appropriate direction.

When the load is reduced the rod *e* also turns the lever *l* pivoted to it at *m*, upon its fulcrum pin *n* that is carried by the 55 bracket *o*. The opposite end of the lever *l* is connected by links *p* to a sleeve *q* adapted to slide on the spear-rod *r* which is provided with two shoulders *s* and a spring *u*. The spear rod has a head *v* at one end that co-60 operates with the aperture *w* in the nozzle *c* to regulate the amount of water delivered by the jet and is guided by a bearing *x* and passes out of the conduit *y* through the labyrinth packing *z*, a gland or any other suitable device.

The opposite extremity of the spear-rod *r* is connected to the plunger *1* of an oil cylinder *2* whose opposite ends are connected by a pipe *3* provided with a valve *4* to regulate the speed at which the oil can be transferred from the front end of the cylinder to the rear. The plunger *1* is provided with one or more valves *5* which allows the oil to pass freely through them from the back to the front of the cylinder when the spear-head *v* 70 is moved in the direction to increase the area of the aperture *w*. The deflector *f* is provided with a stop *f*¹ that engages a projection *f*² formed on an adjacent part when the turbine is running with full load. 80

In operation the sleeve *q* is moved in the direction to compress the spring *u* when the deflector *f* is turned into the position shown in Fig. 2 thereby applying a yielding pressure to the shoulder *t* that causes the spear-rod *r* to move in the direction to reduce the area of the aperture *w* at a speed controlled by the rate at which the oil in the front part of the cylinder *2* can be transferred through the pipe *3* to the rear end 90 of the cylinder which may be adjusted by the valve *4*.

So soon as the speed of the turbine has been reduced by the smaller quantity of water delivered to the buckets by the nozzle *c* the rod *e* will be moved automatically if a 95 governor is employed or by hand, in the reverse direction until the deflector *f* assumes a position in which the reduced jet just escapes the edge of the surface *i* and the edge *j* of the deflector. This movement will result in a re-adjustment of the jet-controlling valve until a position is reached in which the aforesaid relationship is maintained. When the sleeve *q* is moved in a rearward 100 direction owing to an increase in the load, such movement is transmitted directly through the shoulder *s* to the spear-rod *r* whose operation in that direction is not retarded by the oil in the cylinder *2*. 105

I claim:

1. An improved controlling device for impulse turbines comprising a balanced tubular jet deflector supported in bearings and formed on opposite sides of its bore and of the axis of said bearing with deflecting portions, said deflecting portions being formed with cooperating surfaces to be operated upon by the deflected portions of said jet, so that such action on one said deflecting portion will counterbalance the action on the other said deflecting portion. 115

2. An improved controlling device for impulse turbines comprising a balanced tubular deflector through the bore of which the power jet normally passes coaxially, transverse bearings to support said deflector, said deflector having two intercepting portions situated on opposite sides of the bore of said deflector and on opposite sides of 120 125 130

the axis of said bearing and moved into and out of said jet according to the direction and degree of movement of said deflector in its bearing, said intercepting portions having 5 surfaces against which the deflected portions of said jet impinge so as to tend to turn the deflector in reverse directions and means of gradually inserting both intercepting portions into said jet at the same 10 time to deflect a portion of said jet away from the turbine buckets and to balance the turning moments produced by the jet impinging on the intercepting portions of the deflector substantially as set forth.

15 3. An improved controlling device for impulse turbines comprising a balanced tubular deflector through the bore of which the power jet normally passes coaxially, transverse bearings to support said deflector, said deflector having two intercepting portions situated on opposite sides of the bore of said deflector and on opposite sides of the axis of said bearing and moved into and out of said jet according to the direction and degree of movement of said deflector in its bearing, said intercepting portions having surfaces against which the deflected portions of said jet impinge so as to tend to turn the deflector in reverse directions, means of gradually inserting both intercepting portions into said jet at the 20 same time to deflect a portion of said jet away from the turbine buckets and to balance the turning moments produced by the jet impinging on the intercepting portions of the deflector, a jet controlling valve, a valve rod, a conical head at one end of said valve rod, a plunger connected to said rod, a cylinder in which said plunger is adapted to slide, fluid in said cylinder, a valve in 25 said plunger to permit said fluid to pass in one direction, a channel to allow said fluid to pass from one end of said cylinder to the other in the opposite direction, a valve in said channel to adjust the speed at which said fluid passes, two fixed shoulders on said valve rod, a sliding collar between said shoulders, a spring between said collar and the forward shoulder, a lever connected to said collar, a rod connected to said lever and to the deflector actuating means and means of operating said rod, substantially as set forth.

30 40 35 40

3. An improved controlling device for impulse turbines comprising a balanced tubular deflector through the bore of which the power jet normally passes coaxially, transverse bearings to support said deflector, said deflector having two intercepting portions situated on opposite sides of the bore of said deflector and on opposite sides of the axis of said bearing and moved into and out of said jet according to the direction and degree of movement of said deflector in its bearing, said intercepting portions having surfaces against which the deflected portions of said jet impinge so as to tend to turn the deflector in reverse directions, means of gradually inserting both intercepting portions into said jet at the same time to deflect a portion of said jet away from the turbine buckets and to balance the turning moments produced by the jet impinging on the intercepting portions of the deflector, a jet controlling valve, a valve rod having two fixed shoulders thereon, a sliding collar between said shoulders, a spring between said collar and the forward shoulder, a lever connected to said collar, a rod connected to said lever and to the deflector actuating means and means of operating said rod, substantially as set forth.

4. An improved controlling device for

impulse turbines comprising a balanced tubular deflector through the bore of which the power jet normally passes coaxially, transverse bearings to support said deflector, said deflector having two intercepting portions situated on opposite sides of the bore of said deflector and on opposite sides of the axis of said bearing and moved into and out of said jet according to the direction and degree of movement of said deflector in its bearing, said intercepting portions having surfaces against which the deflected portions of said jet impinge so as to tend to turn the deflector in reverse directions, means of gradually inserting both intercepting portions into said jet at the 45 same time to deflect a portion of said jet away from the turbine buckets and to balance the turning moments produced by the jet impinging on the intercepting portions of the deflector, a jet controlling valve, a valve rod, a conical head at one end of said valve rod, a plunger connected to said rod, a cylinder in which said plunger is adapted to slide, fluid in said cylinder, a valve in 50 said plunger to permit said fluid to pass in one direction, a channel to allow said fluid to pass from one end of said cylinder to the other in the opposite direction, a valve in said channel to adjust the speed at which said fluid passes, two fixed shoulders on said valve rod, a sliding collar between said shoulders, a spring between said collar and the forward shoulder, a lever connected to said collar, a rod connected to said lever and to the deflector actuating means and means of operating said rod, substantially as set forth.

In testimony whereof, I have signed my name to this specification at 61 and 62 Chancery Lane, in the county of London, England, this 3rd day of September, 1926.

PERCY HECTOR PITMAN.
